UNITED STATES PATENT OFFICE.

JAMES KENYON, JONATHAN BARNES, AND RICHARD WALTON KENYON,
OF ACCRINGTON, COUNTY OF LANCASTER, ENGLAND.

VICE.

SPECIFICATION forming part of Letters Patent No. 365,186, dated June 21, 1887.

Application filed September 13, 1886. Serial No. 213,427. (No model.) Patented in England May 17, 1886, No. 6,617.

To all whom it may concern:

Be it known that we, JAMES KENYON, JONATHAN BARNES, and RICHARD WALTON KENYON, of Accrington, Lancaster county, England, have invented certain new and useful Improvements in Vises, (patented in England on the 17th day of May, 1886, No. 6,617,) of which the following is a specification.

At the present time there are known in the art numerous vises with sliding jaws having ratchet-teeth thereon to engage locking devices operated by rotary shafts or screws, so that the jaws may be instantly released in order to be moved by hand, and it is to this class of vises that our invention relates.

In practice it is found desirable to tighten the jaws by means of a screw after the locking devices are brought into play.

Our invention relates to an improved construction and arrangement under which this mode of action is secured.

In the accompanying drawings, Figure 1 is a longitudinal vertical section of our vise. Fig. 2 is a rear end view of the same. Fig. 3 is a front view of the upper parts. Fig. 4 is an end view of the cam.

Referring to the drawings, A represents the movable jaw, having a horizontal arm, which slides through an opening in the stationary jaw B. The jaw B contains a fixed rack, C, overlying the arm of the movable jaw to engage a small rack-plate, D, lying loosely in said arm, and sustained by a cam, E, on which it rests, and by which it is raised into action when the vise is to be locked. The cam is fastened, as shown in Figs. 1 and 2, on a horizontal rock shaft or spindle, F, extending through the movable jaw from front to rear and capable of sliding endwise therein to a limited extent.

An encircling spring, K, bearing against a shoulder on the spindle, and another on the sliding jaw, urges the spindle rearward, and a pin, L, projecting from the spindle in position to encounter a shoulder, M, limits the rotary motion of the spindle to a half-revolution. The forward end of the spindle is formed with a screw-thread, f, and provided with a nut, G, which is connected with the spindle with friction devices of any appropriate character which will tend to revolve the spindle with

the nut. In the form shown in the drawings the friction devices consist of a second nut, H, mounted on the threaded portion of the spindle and connected with the first nut by a loose pin, I, compelling the two to turn together, and of a strong spiral spring, II, seated between the nuts and urging them apart, so that they bind upon the thread. A handle or lever, G', is applied to the main nut G as a means of turning the same, and a head, J, is secured to the end of the spindle to prevent the escape of the nuts, and, as shown in the drawings, the contiguous faces of the nut H and the head T are provided with lugs x, adapted to engage and to impart positive motion to the spindle in the event of its binding until the nuts are turned outward against the head.

The operation is as follows: When the operator, grasping the lever or handle G', turns the nut G to the right, the friction devices cause the shaft to turn therewith until the cam E lifts the plate D into engagement with the rack on the stationary jaw, the effect of which is to prevent the movable jaw from opening, the further rotation of the spindle being prevented by its stop-pin, or by the friction of the eccentric against the plate D. The nut G, overcoming the resistance of the friction devices, turns upon the spindle, and, being moved by the screw-thread along the spindle, so it urges the movable jaw toward its companion with great force. When the nut G is turned in the opposite direction, it revolves around the screw and loosens the jaws, after which the friction devices turn the spindle with the nut, causing the cam E to lower the plate D out of engagement with the overlying rack. The effect of this action is to entirely unlock the movable jaw, so that it may be moved inward or outward at will by hand.

We are aware that a screw has been provided with a wedge acting to lift the block into position to lock the jaw of a vise and thereafter to urge the block endwise for the purpose of closing the jaw, and this we do not claim; but we believe ourselves to be the first to combine with a closing nut mounted on a rotary shaft or spindle friction devices through which the nut may impart a rotary motion to the shaft and cause the latter to actuate the

devices for locking the jaws, and it will be manifest to the skilled mechanic that the construction herein described and shown may be varied in the form and arrangement of the 5 details without changing its mode of action or passing beyond the limits of our invention.

Having thus described our invention, what we claim is—

1. In a vise, the stationary jaw and its rack, to in combination with the sliding jaw, the movable rack-plate therein, the longitudinal shaft provided with a screw-thread and with a cam to adjust the movable rack, the nut mounted on the threaded portion of said shaft, and a 15 friction device connecting said nut with the shaft, substantially as described, whereby the nut is enabled to turn the shaft for the purpose of engaging the racks, and thereafter permitted to turn upon the shaft for the purpose of 20 closing the jaws.

2. In a vise of the type herein described, the combination of the jaws, a locking mechanism, substantially as described, to hold the jaws, a rotatable shaft to operate said locking 25 mechanism, provided with a screw-thread, and a nut to tighten the jaws mounted on said shaft and connected therewith by a friction device, substantially as described, whereby the nut is enabled to serve the double function 30 of turning the shaft to operate the locking device and of turning upon the shaft to tighten the jaws.

3. In a vise, and in combination with the rock-shaft for locking and unlocking the jaws, the nut mounted on a threaded portion of said shaft to close the jaws, the second nut, also mounted on said shaft, and the intermediate spring, whereby the nuts are caused to bind upon the shaft, as and for the purpose described. 35

4. In a vise, and in combination with the rock-shaft for operating the locking device, the two nuts mounted on a threaded portion of said shaft, the intermediate spring, and the head or enlargement at the end of the shaft, 45 whereby it may be given a positive rotation.

5. The combination of the stationary jaw and its rack, the sliding jaw and its adjustable rack-plate, the rock-shaft mounted in the movable jaw, the cam on said shaft, the spring 50 *k*, the two nuts, and the spring between the nuts, said parts constructed and combined for joint operation, substantially as described.

In testimony whereof we have signed our names to this specification in the presence of 55 two subscribing witnesses.
